Primary Examiner — George D. Kirschbaum*Assistant Examiner* — Joseph J Kukella(74) *Attorney, Agent, or Firm* — Seed IP Law Group LLP(57) **CLAIM**

The ornamental design for an anti-theft package alarm, as shown and described.

DESCRIPTION

FIG. 1 is a perspective view of an anti-theft package alarm showing my new design.

FIG. 2 is a top plan view thereof.

FIG. 3 is a bottom plan view thereof.

FIG. 4 is a front elevational view thereof.

FIG. 5 is a left side elevational view thereof; and,

FIG. 6 is a right side elevational view thereof.

The rear elevational view of the anti-theft package alarm is a mirror image of the front elevational view shown in FIG. 4.

The broken lines in the figures constitute part of the disclosure, but designate portions of the design that are not claimed.
